UNITED STATES PATENT OFFICE.

GOODRICH Q. LEWIS, OF WHEATON, ILLINOIS, ASSIGNOR TO WILLIAM H. MINER, OF CHICAGO, ILLINOIS.

DRAFT-RIGGING FOR RAILWAY-CARS.

1,123,328.

Specification of Letters Patent.

Patented Jan. 5, 1915.

Application filed July 7, 1913. Serial No. 777,626.

To all whom it may concern:

Be it known that I, GOODRICH Q. LEWIS, a citizen of the United States, residing at Wheaton, in the county of DuPage and State of Illinois, have invented a certain new and useful Improvement in Draft-Rigging for Railway-Cars, of which the following is a full, clear, concise, and exact description, reference being had to the accompanying drawings, forming a part of this specification:

My invention relates to improvements in draft rigging for railway cars.

The object of my invention is to provide a draft rigging of high capacity, and of cheap and simple construction.

In the drawings forming a part of this specification—Figure 1 is a plan view partly in longitudinal section on line 1—1 of Fig. 2 of a draft rigging embodying my invention; Fig. 2 is a side elevation partly in longitudinal section on line 2—2 of Fig. 1; Fig. 3 is a plan view partly in longitudinal section showing the position of the parts in full draft; Fig. 4 is a plan view partly in longitudinal section showing the position of the parts in full buff; Fig. 5 is a half cross section on line 5—5 of Fig. 1; Fig. 6 is a half cross section on line 6—6 of Fig. 1; Fig. 7 is a perspective view of the friction shell; Fig. 8 is a perspective view of the movable spring seat; Fig. 9 is a perspective view of the follower; Fig. 10 is a perspective view of the wedge; Fig. 11 is a perspective view of one of the antifriction rolls; and Fig. 12 is a perspective view of one of the friction shoes.

Referring to the drawings 13, 13 represent draft sills or parts of the car frame to which the draft rigging is applied. Secured to the draft sills are the cheek plates 14, 14, each having the front stop shoulders 15, 15, front limiting stop shoulders 16, 16, rear limiting stop shoulders 17, 17, and rear stop shoulders 18, 18. The cheek plates illustrated in Fig. 1 of the drawings are well known, and now widely used.

The numeral 19 represents a draw bar, 20 a yoke connected thereto, preferably by the key 21 passing through the yoke and draw bar, and through the elongated slots 22 in the draft members and cheek plates. The tie plate 23 supports the yoke and the draft gear 24 mounted between the draft mem-

bers. The draft gear 24 comprises a short 55 friction shell 25, friction mechanism 26 within the shell, the movable spring seat 27, the springs 28 and the rear follower 29.

The friction shell 25 is preferably cylindrical in shape, and substantially of the same length as the friction mechanism. At either side it is provided with lugs or projections 30, 30 adapted to engage within the slots 31, 31 formed within the cheek plates, and thus rigidly secure the shell in a stationary position between the draft members. I prefer to forwardly extend the projections 30, 30 so as to adapt the shell with the other parts of the draft gear to mounting within the draft members in connection with the widely used stop members hereinbefore described, and in which the slots 31, 31 are formed by the front stops 15 at the forward end and the front limiting stops 16 at the rear end. In this construction a recess 32 is formed between the recesses 31, 31 within which the butt of the draw bar reciprocates. The movable spring seat 27 is provided with a shoulder 33, adapted to engage the rear end of the friction shell 25 in the normal position of the gear, and in pulling movement thereof. The said movable spring seat is provided with a forwardly extending collar 34, which engages the rear ends of the friction shoes 35 of the friction mechanism 26. The said friction shoes 35 are preferably three in number, each having an outer friction face 36 and an inner wedging face 37.

The wedge 38 of the friction mechanism is preferably pyramidal in form, and is provided with wedging faces 39 equaling in number the friction shoes. An antifriction roller 40 is disposed between each wedging face 39 of the wedge and the opposed wedging face 37 of a friction shoe. The forward face 41 of the wedge 38 engages the rear end of the draw bar, and is provided with a recess 42 to receive the head 43 of the connecting rod 44, which passes through the wedge, through the perforation 45 in the movable spring seat 27, and through the perforation 46 in the rear follower 29, the rear follower being provided with a recess 47 to receive the nut 48 of the said connecting rod.

The springs 28 are preferably three in number in nested arrangement, all of said springs being forwardly seated against the movable spring seat 27, the inner spring 50

being seated against the boss 51 with which the forward face of the rear follower 29 is provided, the intermediate spring 52 being seated against radial extensions 53 from said boss 51, and the outer spring 54 being seated in a recess 55 formed between the boss 51 and forwardly extended flanges 56 with which the forward face of the rear follower 29 is provided.

10 On rearward movement of the draw bar the friction mechanism is brought into frictional action with the shell, the movable spring seat 27 is forced rearwardly by the friction shoes, the rearward movement of said spring seat being meanwhile resisted by the springs 28. By reason of the rigid engagement of the friction shell and cheek plates the shock transmitted by the draw bar to the draft gear is distributed along the entire length of the attachment of the cheek plates to the draft members. The position of the parts of the draft gear in full buff is illustrated in Fig. 4 of the drawings.

25 On forward movement of the draw bar the movable spring seat engages the rear end of the friction shell, and the draft yoke draws the rear follower forwardly, compressing the springs between the rear follower and the spring seat 27, which is stopped against forward movement by the stationary shell. On forward movement of the draw bar it will be clear that the friction elements are not brought into frictional action, the gear being a spring gear in pulling movement and a spring and friction gear in buffing movement.

I claim:

1. In a draft rigging for railway cars, draft members, a stationary shell rigidly secured thereto, a draw bar, rear follower and draft yoke, friction mechanism within the shell, springs without the shell operatively connected to the friction mechanism and the draft yoke, the shell being forwardly provided with a recess, the draw bar engaging the friction mechanism and being adapted to reciprocate in said recess. 45

2. In a draft rigging for railway cars, draft members, stop members secured thereto, a shell, friction mechanism in the shell, a draw bar, yoke and springs operatively connected with the friction mechanism, the shell being provided with forwardly extended lateral arms to engage the stop members and rigidly secure the shell thereto. 50

3. In a draft rigging for railway cars, draft members, a stationary shell rigidly mounted on said members, a draw-bar, a yoke connected to said draw-bar, friction mechanism within the shell, said mechanism including friction shoes and a wedge, portions of which are normally extended forwardly beyond the end of the friction shell, said shell being provided with forwardly extended lateral arms engaging the draft members and between which the rear end of the draw-bar is adapted to reciprocate upon inward movements of the latter. 55

GOODRICH Q. LEWIS.
